CLAIM

The ornamental design for a combined biodegradable litter box and splash guard, as shown and described above.

DESCRIPTION

FIG. 1 is a front perspective view of a combined biodegradable litter box and splash guard;

FIG. 2 is a rear perspective view thereof;

FIG. 3 is a top plan view thereof;

FIG. 4 is a front elevation view thereof;

FIG. 5 is a right side elevation view thereof;

FIG. 6 is a back elevation view thereof;

FIG. 7 is a left side elevation view thereof;

FIG. 8 is a bottom plan view thereof;

FIG. 9 is a perspective view thereof showing the splash guard in an alternate position;

FIG. 10 is a perspective view thereof showing the splash guard in a collapsed position; and,

FIG. 11 is another rear perspective view thereof showing the cover in an alternate position.

The broken lines are for illustration only and form no part of the claimed design.
